(57) **CLAIM**

I claim the ornamental design for an oral care product dispenser, as shown and described.

DESCRIPTION

FIG. 1 is a perspective view of an oral care product dispenser.

FIG. 2 is a front view of the dispenser of FIG. 1.

FIG. 3 is a rear view of the dispenser of FIGS. 1-2.

FIG. 4 is a right side view of the dispenser of FIGS. 1-3.

FIG. 5 is a left side view of the dispenser of FIGS. 1-4.

FIG. 6 is a top view of the dispenser of FIGS. 1-5; and,

FIG. 7 is a bottom view of the dispenser of FIGS. 1-6.

The broken lines in the drawings are included for the purpose of illustrating portions and environmental structure of the oral care product dispenser and form no part of the claimed design.

The nature and intended use of the claimed design includes dispensing of oral health care products (e.g., mouthwash, fluoride rinses, toothpaste, other viscous fluids, such as gels and pastes, or the like), either directly therefrom or in a tablet or encapsulated form.
